UNITED STATES PATENT OFFICE.

CHARLES J. HODGE, OF HOUGHTON, MICHIGAN.

DESIGN FOR A SCREEN-SUPPORTING FRAME FOR MINERAL OR ORE WASHING JIGS.

SPECIFICATION forming part of **Design No. 30,106**, dated **January 31, 1899**.

Application filed January 7, 1899. Serial No. 701,525. Term of patent 7 years.

To all whom it may concern:

Be it known that I, CHARLES J. HODGE, a citizen of the United States, residing at Houghton, in the county of Houghton and State of Michigan, have invented and produced a certain new and original Design or Useful Shape for a Screen-Supporting Frame for Mineral or Ore Washing Jigs, of which the following, in connection with the accompanying drawings, is a full, clear, and exact specification.

In the said drawings, Figure 1 is a plan view of a screen-supporting frame of the character described embodying my design. Fig. 2 is a transverse sectional view thereof, taken on the line 2 2, Fig. 1; and Fig. 3 is a side elevation, partly in section, taken on the line 3 3, Fig. 1.

The leading features of my design consist of a frame for supporting jig-screens having the marginal frame portion A and the longitudinal and transverse aligned cross-bars B C, forming the oblong spaces, as clearly shown in Fig. 1, and being very narrow as compared with their depth, as shown in Figs. 2 and 3.

The marginal frame A is rectangular and constitutes an oblong, and its inner upper edges are beveled downwardly, as shown at a, between the points where the cross-bars B C

adjoin it and also the points where are located a number of circular socketed bosses a'. The 30 marginal frame A is very narrow as compared with its depth, and it is coterminous in depth with the bars B C, which are also very narrow as compared with their depth and are considerably narrower than the frame portion A. The longitudinal bars B are also coterminous in height with the frame portion A; but the transverse bars C have their upper edges formed on down-curves, as clearly shown at c, Fig. 2, thus presenting in cross-section on the line 2 2, Fig. 1, the appearance of waves whose apexes are situated at the upper edges of the longitudinal bars B. The bars B C are also tapered from bottom to top, as shown in Figs. 2 and 3, and their upper 45 edges are rounded.

Having thus described my invention, what I claim as new therein, and desire to secure by Letters Patent, is—

The design for a screen-supporting frame 50 for mineral or ore washing jigs substantially as herein shown and described.

CHARLES J. HODGE.
